UNITED STATES PATENT OFFICE.

FREDERICK KAMPFE, RICHARD KAMPFE, AND OTTO KAMPFE, OF BROOKLYN, NEW YORK.

DESIGN FOR A RAZOR-BLADE HOLDER.

SPECIFICATION forming part of Design No. 24,093, dated March 12, 1895.

Application filed February 1, 1895. Serial No. 537,018. Term of patent 7 years.

To all whom it may concern:

Be it known that we, FREDERICK KAMPFE, RICHARD KAMPFE, and OTTO KAMPFE, citizens of the United States, and residents of Brooklyn, in the county of Kings and State of New York, have invented a new and original Design for Razor-Blade Holders, of which the following is a specification.

In the accompanying drawings, forming a part of this specification and in which like letters of reference indicate like parts in all the figures: Figure 1, is a perspective view of our new design for razor blade holders. Fig. 2, is a rear elevation of the same.

The leading feature of our design consists in a razor blade holder, substantially U shaped in cross section and having a series of apertures arranged longitudinally in its back.

In the drawings, A is the razor blade holder,

which is approximately U shaped in cross section and B are the apertures, located in a longitudinal row in the back of the said holder.

Having thus described our invention, what we claim as new, and desire to secure by Letters Patent, is—

The design for a razor blade holder, substantially as herein shown and described.

In testimony that we claim the foregoing as our invention we have signed our names, in presence of two witnesses, this 3d day of January, 1895.

FREDERICK KAMPFE.
RICHARD KAMPFE.
OTTO KAMPFE.
